Primary Examiner — Bao-Yen T Nguyen

Assistant Examiner — Emily Anna Saunders

(57) **CLAIM**

The ornamental design for a educational toy as shown and described.

DESCRIPTION

FIG. 1 is a front, right, and top perspective view of the educational toy, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines in the drawings depict portions of the educational toy that form no part of the claimed design. The broken lines depicting the boundary of the educational toy in FIGS. 2 and 8 form no part of the claimed design.

1 Claim, 8 Drawing Sheets
